William L. Bonar, Moundsville, W. Va., assignor
to Louis Marx & Company, Inc., New York,
N. Y., a corporation of New York

Application December 16, 1952, Serial No. 22,733

Term of patent 7 years

(Cl. D34—15)

To all whom it may concern:

Be it known that I, William L. Bonar, a citizen of the United States and a resident of Moundsville, in the county of Marshall and State of West Virginia, have invented a new, original, and ornamental Design for a Toy Railroad Station, of which the following is a specification, reference being had to the accompanying drawings, forming a part thereof, wherein:

Fig. 1 is a front elevational view of a toy railroad station, showing my new design;

Fig. 2 is a top plan view thereof;

Fig. 3 is an end elevational view thereof;

Fig. 4 is an opposite end elevational view thereof; and

Fig. 5 is a rear elevational view thereof.

I claim:

The ornamental design for a toy railroad station, substantially as shown.

WILLIAM L. BONAR.
